UNITED STATES PATENT OFFICE.

HAS CLARK, OF KANSAS CITY, KANSAS.

DESIGN FOR A HORSE-COLLAR.

SPECIFICATION forming part of Design No. 33,228, dated September 18, 1900.

Application filed August 7, 1900. Serial No. 26,199. Term of patent 7 years.

To all whom it may concern:

Be it known that I, HAS CLARK, a citizen of the United States, residing at Kansas City, in the county of Wyandotte and State of Kansas, have invented and produced a new and original Design for Horse-Collars, of which the following is a specification, reference being had to the accompanying drawings, forming part thereof.

10 My invention relates to horse-collars, and has for its object the provision of a new, useful, and ornamental design for the same.

15 In the accompanying drawings, Figure 1 represents a perspective view of a horse-collar embodying my design. Fig. 2 is a front view. Fig. 3 is a side view.

20 Referring to the drawings, it will be seen that the leading or material feature of the design consists in an ovoidal band having its front and rear edges extending approximately parallel, the lower portion of the sides being slightly enlarged, which effect is produced primarily by the convex curvature of its rear edge; also, in the peculiar configuration of 25 the ovoidal band, the same flaring from the perimeter of its front edge to the perimeter of its rear edge, and in the representations of looped brackets or plates at the outer sides of the collar about centrally of said enlarged 30 portions, with the loops extending vertically; also, in the representation of ornamental pan-

els on the outer sides of the collar, said panels conforming approximately to the outline of the collar and terminating near its lower end in tongue-like ends.

35

Minor features of the design reside in the representation of a strap and buckle at the top of the collar.

36 In detail, 1 designates the ovoidal band, having the lower portion of its front edge enlarged, as at 2, by the convex curvature 3 of the lower portion of the rear edge.

40 4 designates the looped brackets or plates at the outer sides of the collar and arranged about centrally of the enlarged portions 2.

45

6 designates the representation of the strap, and 7 the buckle at the top of the collar.

46 8 designates the representation of panels on the sides of the collar, and 9 the tongue-like terminations thereof.

50

Having described the invention, what I claim as new, and desire to secure by Letters Patent, is—

55 The design for a horse-collar herein shown and described.

In testimony whereof I affix my signature in the presence of two witnesses.

HAS CLARK.
